INCANDESCENT ELECTRIC LAMP

Marcel Charles Perrin and Jean Eugène Vinzant,
Paris, FranceApplication April 21, 1933, Serial No. 667,182
In France May 12, 1932

7 Claims. (Cl. 176—29)

The object of the present invention is to provide an incandescent electric lamp capable of many applications. The invention also aims at producing a lamp of great simplicity and very substantial and of little cost, as a result of a simplification in the working of the glass. More particularly its object is to do away with fragile supports, such as small rods of glass, which are frequently used in such lamps.

10 A further object of the invention is to provide tubular lamps such as in the form of letters, for luminous signs characterized by great simplicity of construction and allowing of the use of tubes of great length of small diameter and of the most varied forms.

Electric lamps in which the foregoing objects are attained have the characteristic features specified in the following description and in the claims appended to the end of this description.

20 Fig. 1 is an elevation of a tubular lamp having the form of a letter.

Fig. 2 is a longitudinal sectional view of the tube in the course of mounting.

Fig. 3 is a transverse section of a tubular lamp taken on the line 3—3 in Fig. 2.

25 Fig. 4 is an elevation of a tubular lamp having the form of an arc of a circle.

Fig. 5 is an elevation of a cut plate support forming a constituent element of the lamp shown in Fig. 4.

30 Fig. 6 is a perspective view on a larger scale showing the assembling of the supporting elements of Fig. 5.

Fig. 7 represents a detail of one of the supports shown in Fig. 6.

35 The tubular lamp illustrated in Fig. 2 consists essentially of a glass envelope in the form of a cylindrical glass tube 1 in which the filament 4 is carried by several insulating support members 5¹, 5², 5³ . . . mounted in the interior of the glass tube 1 and themselves maintained in their correct positions by a support wire 15.

40 One extremity of the filament 4 is connected to one of the electrodes 3¹ conveying current thereto, while the other end of the filament 4 is connected to the support wire 15 which serves as a return current conductor and is connected to a second electrode 3².

45 Each insulating support element 5 is preferably in the form of a triangle or of some modification of a triangle so that this support bears at three points on the inner surface of the glass tube 1 and thus ensures the precise centering of the filament 4 relatively to the glass tube 1.

50 Each insulating support element 5 carries on

its concave side, suspensions members, such as hooks, eyelets, etc. 16 . . . which are secured in the body of the insulating support and serve to carry the filament; in addition these insulating support elements 5 comprise fixing means such as clasps 17 or slits 18, by which the said elements are mounted on the support wire 15.

In any case, the support members and the suspension members which they carry are mounted within the glass tube 1 in the following manner;

(a) The plates of mica 5¹, 5² . . . are cut into triangular form.

(b) The suspension members or clasps 16 are fixed on the cut plates 5¹, 5² . . .

(c) All the plates 5¹, 5² . . . are then mounted 15 on the support wire 15.

(d) The filament 4 is inserted into the suspension members 16 carried by the plates 5¹, 5² . . .

(e) With the aid of the support wire 15, the chain thus formed is passed into the interior of 20 the glass tube 1 in such a manner that the plates take up a position parallel to the axis of the tube. This glass tube 1 is provided further with a flared or bell-shaped mouth 1¹ which allows of the ready insertion of the support elements 5¹, 5², 5³ . . . 25

(f) The electrical connections to the two extremities of the filament are secured, one end being joined up directly to the electrode 3¹, while the other extremity is joined up to the support wire 15, which acts as the return current conductor and is connected to the second electrode 3². 30

(g) A vacuum is produced within the tube which is then sealed at both its extremities.

The support elements 5¹, 5² . . . are preferably of a height greater than the inner diameter of 35 the glass tube 1, so that these support members 5¹, 5² can be given a curvature to allow of their being easily introduced into the glass tube and maintained there subsequently simply by their elasticity, while at the same time they are supported on the inner surface of the glass tube.

The suspension member 16 of the filament 4 is bent into a curved form for part of its length and co-operates in retaining the supporting element in its curved position.

45 In the foregoing example, it has been understood that the supporting elements 5¹, 5² . . . were independent of each other and were arranged parallel to the axis of the glass tube 1.

In the particular construction shown in Fig. 5, 50 these various support elements 5¹, 5² . . . are assembled in such a manner relatively to each other as to form a continuous chain extending over the whole length of the glass tube.

Further, the part of these support members 55

which carries the filament 4 is arranged at right angles to the axis of the glass tube.

The chain support consisting entirely of insulating material such as, for instance, mica, possesses a high degree of suppleness and is particularly suitable for use in connection with the equipment of bent tubes of every shape. This chain is made up of plates 30 (Fig. 6), the central tongue or blade 31 of which, once it is raised, serves as a support for the filament 4.

These plates are attached to each other by means of clips 32 (Fig. 7), which at the same time, maintain the tongue 31 in the vertical position at right angles to the axis of the tube.

15 The flexible chain in question may be maintained in position by the mica blades 34¹ forming a spring and bearing on the inner wall of the tube 1. In Figs. 6 and 7 will be seen a spring blade 34¹ secured on the tongue 31.

20 As a result of the above methods of construction there can be provided electric lamps of very simple construction and of low production costs and at the same time not at all fragile, as a result of doing away with the usual glass supporting rods.

25 Furthermore, the avoidance of the usual metallic supports sealed at one end in the small glass rod gets rid of a source of vibration which prevents the satisfactory preservation of the filament. These advantages, which are valuable enough for ordinary lamps, possess a special interest in the case of straight or bent tubular lamps, because the arrangements adopted up till now necessitate a limitation of the length of the tubes owing to the fragility of the supports; furthermore, the strengthening of the latter and their mounting compels the makers to employ tubes in which the diameter, which must increase with the length, renders the lamp cumbersome.

40 With the arrangement provided by the invention, it becomes possible to construct tubular lamps of small diameter and of any length, whatever their form may be; the tubes in question may, further, be worked, folded or bent even 45 after the supports and the filament have been mounted. They lend themselves particularly to the reproduction of decorative devices and of luminous signs.

What we claim as our invention and desire to 50 secure by Letters Patent is:—

1. In an electric lamp comprising a glass tube and electrodes, the combination of a plurality of independent flexible supports of insulation mounted in the glass tube, a filament carried by said independent supports and connected to the electrodes, and connecting means independent of the filament for connecting the independent supports to form an adjustable flexible connection.

2. In an electric lamp comprising a glass tube and electrodes, the combination of a plurality of independent flexible supports of insulation mounted in the glass tube, a filament carried by said independent supports and connected to the

electrodes, and a supporting wire independent of the filament and mounted in the glass tube for flexibly connecting the said independent supports.

3. In an electric lamp comprising a glass tube and electrodes, the combination of a plurality of independent flexible supports of insulation, each of said supports in normal conditions being of a height in excess of the inner diameter of the glass tube, said supports being mounted in the glass tube in deformed state and being held therein by elasticity, a filament mounted on the said supports and connected to the electrodes, and connecting means independent of the filament for flexibly connecting the said independent supports. 5

4. In an electric lamp comprising a glass tube and leads, the combination of a plurality of independent flexible supports of insulation, each of said supports being of a height in excess of the inner diameter of the glass tube, said supports being mounted in the glass tube in deformed state and being held therein by elasticity, a curved suspending means carried by and assuming the form of each of the said deformed supports, a 10 filament mounted upon the said suspending means and connecting the said leads. 15

5. In an electric lamp comprising a glass tube and leads, the combination of a plurality of independent flexible supports of insulation mounted in the glass tube, each of said supports having polygonal form and abutting with its corners the inner surface of the glass tube, a filament mounted upon the independent supports and connected to the leads, connecting means independent of the filament for flexibly connecting the said independent supports. 20

6. In an electric lamp comprising a glass tube and leads, the combination of a plurality of independent flexible supports of insulation mounted in the glass tube, each of the said supports consisting of a plate provided with an upstanding central tongue, a filament carried by the said central tongues and connected to the leads, connecting means independent of the filament and connecting the said plates to one another, said plates forming the said independent flexible supports. 25

7. In an electric lamp comprising a glass tube and leads, the combination of a plurality of independent flexible supports of insulation mounted in the glass tube, each of said supports consisting of a plate having an upstanding central tongue, a spring disposed on an independent support and abutting the inner surface of the glass tube, a filament carried by said upstanding central tongues of the supports and connected to the leads, connecting means independent of the filament for flexibly connecting the said plates to one another, the said plates forming said independent supports. 30
